UNITED STATES PATENT OFFICE.

GEARY Y. THORNTON, OF OAKLAND, OREGON.

MILKING DEVICE.

1,262,871.

Specification of Letters Patent. Patented Apr. 16, 1918.

Application filed February 15, 1917. Serial No. 148,827.

To all whom it may concern:

Be it known that I, GEARY Y. THORNTON, a citizen of the United States, residing at Oakland, in the county of Douglas and State 5 of Oregon, have invented certain new and useful Improvements in Milking Devices, of which the following is a specification.

This invention relates to devices for dilating cavities and canals and the object of 10 the same is to provide a device that is especially adapted for use in milking cows.

More specifically, this invention contemplates the production of an instrument for insertion in the teat of a cow when the same 15 is in such condition as to preclude squeezing thereof.

Another object of this invention is to provide a dilating instrument that is so constructed as to provide for its ready insertion 20 in a teat of a cow and after its insertion portions thereof being moved relatively to dilate the teat so that the cow can be "milked" without permanent injury or pain to her.

25 A still further object of this invention resides in the production of a device of the kind described that will secure the dilating members of the instrument in a fixed position in operation.

30 A still further object of this invention is to provide means for use in connection with this dilator for efficiently "milking" the cow.

A still further object of this invention is to provide a dilating instrument of the 35 kind above described that is simple in construction, efficient in operation and consists of the minimum number of parts.

With these and other objects in view, this 40 invention consists of certain novel constructions, combinations and arrangements of parts, as will be hereinafter fully described and claimed.

In the accompanying drawings:

Figure 1 is a top plan view of the device 45 in a compact position.

Fig. 2 is a view in elevation of the improved device as shown in Fig. 1.

Fig. 3 is a sectional view taken on line 3-3 of Fig. 2.

50 Fig. 4 is a view in elevation of one of the dilating members used in connection with this invention.

Fig. 5 is a view in elevation of one of the supporting plates of this device.

55 Fig. 6 is a view in elevation of the device

for use in connection with the dilator attached to a cow.

Fig. 7 is a view in end elevation of the device as shown in Fig. 6.

Referring to the parts by reference numerals, 10 denotes the post of the instrument having the head or finger engaging portion 11 at one end and the opposite end thereof enlarged and flattened as at 12. A series of plates 13 the same being substantially V-shaped are secured to each side of the enlarged flattened end 12 of the post 10 by means of the tube 14 passing through the aperture 15 one of which is formed in each of the plates 13. At the upper ends of the plates 13 the same are rolled as at 16 and in the opposite ends of the rolled portions 16 are permanently secured stub axles 17 for a purpose to be hereinafter set forth. A plurality of retaining springs are secured 70 to the flattened end 12 of the post 10 at a point lower than the securement of the plates 13, each of said springs 18 having an enlarged head 19 at the free end thereof and a series of teeth 20 on one face thereof. 80

The dilating members are designated in their entirety by the numeral 21 the same being identical in construction and the description of one will suffice. Each of the dilating members comprise a handle portion 85 22 having an enlarged head 23 at the lower end thereof and at the upper end the dilating portion 25 that in turn terminates in the knobs 26. At the junction of the offset portion 24 and the handle 22 are formed 90 a pair of axle receiving tubes 27 that are each adapted to receive one of the stub axles 17 carried by the plates 13. It is to be noted that there are three of the dilating members and they are so arranged and constructed 95 that, when in assembled position, as clearly shown in Figs. 1 and 2, the knobs 26 thereof will form a complete ball and the portions 25 a single standard.

The operation of the device is as follows: 100 The teat of the cow is grasped well adjacent the udder and the milk is therefore brought into the lower portion of the teat. The lower end of the teat which is as before stated, filled with milk projects below 105 the hand and the instrument is grasped by the hand other than the one engaging the teat, the instrument obviously being in an assembled position as shown in Figs. 1 and 2. The ball of the dilator formed by the 110

knobs 26 is to be about the same size as the ordinary stream of milk and is to be inserted in the teat past the natural valve in the teat and then the grip is released on the teat and 5 the dilator expanded that is, the arms 21 rocked upon the stub axles 17 which make a three-cornered passage in the teat. The dilator can then be held in the expanded position by means of the lugs 27 that are carried by the arms 22 in engagement with the teeth 20 on the springs 18. From the foregoing it will be understood that a teat dilating instrument has been provided that will uniformly spread the teat and will in 10 no way injure the same.

In Figs. 6 and 7 I have shown a means for attachment to the cow when the dilators of the kind above described have been inserted in the teat of the cow whereby the 15 milk will be conveyed to a suitable receptacle and any likelihood of the milk becoming germ laden will be obviated.

This attachment includes a pail or receptacle 30 having a top 31 which is provided 20 with a suitable handle 32. A bail 33 is also provided with the receptacle for the obvious purpose. A suitable supply tube 34 is provided, the same having one end thereof attached to the receptacle 30 by means of 25 the union 35 and the opposite end of the same is in connection with the udder receiving bowl 36 by the union 37. The bowl 36 is held in position, as shown in Fig. 6, over the udder, by means of a pair of straps 30 38 that are fixedly secured at diametrically opposite points to the bowl. It is of course 35 to be understood that these straps are of such length as to permit them to pass over the back of the animal and one of the same 40 carries a buckle 39 to engage the other of the straps for the obvious purpose.

After the dilator has been inserted as has been previously described, the bowl 36 can be positioned on the udder of the animal as 45 shown in Fig. 6, by means of the straps 38 and the milk conveyed from the bowl to the receptacle 30 by means of the tube 34. In

this manner, the milk will be excluded from the germ laden air.

It is obvious that minor changes may be 50 made in the form and construction of this invention without departing from the material parts thereof. It is therefore not wished to confine the invention to the exact form herein shown and described, but it is 55 wished to include all such as properly come within the scope claimed.

What is claimed is:

1. In a dilator, a post, a plurality of stub axles supported by said post, a plurality of 60 dilator arms pivoted on said axles, and means for holding said arms in a desired position.

2. A dilator, a post, a plurality of stub axles carried by said post, a plurality of 65 dilator arms pivoted on said axles, and spring means carried by said post for retaining said arms in a desired position.

3. In a dilator, a post, a plurality of substantially V-shaped plates secured to said 70 post, certain of said plates having one of their edges rolled to carry stub axles, a plurality of dilator arms, pivoted on said axles and means for retaining said dilator arms in a desired position.

4. In a dilator, a post, a plurality of dilators having operating arms, means on said post for pivotally carrying said dilators, and means on said post engageable with said arms on said dilators to retain said dilators 80 in a desired position.

5. In a dilator, a post, a plurality of dilators each having an operating arm, means on said arms for pivotally carrying said dilators, and a plurality of springs engageable with said operating arms to retain said dilator in a certain position.

In testimony whereof I affix my signature in presence of two witnesses.

GEARY Y. THORNTON.
